CLEANING, AND FEEDING OF METAL STRIPS TO ROLLS OR ROLLING MILLS

Francis Gerald Ratcliff, Birmingham, England

Application June 1, 1933, Serial No. 673,902
In Great Britain June 18, 1932

1 Claim. (CL 80—43)

This invention comprises certain improvements in or relating to the cleaning of metal strips and the feeding the same to the rolls of rolling mills, and it has for its object an improved appliance 5 which not only effects the cleaning of the strip but also forms a device to feed the same to the rolls of rolling mills.

According to the present improvements, the 10 appliance comprises a press or cleaner through which the strip is drawn to effect the cleaning process, which press or cleaner is movable so that the strip whilst gripped by the press or cleaner can be moved forward to feed the strip between the rolls whilst the rolls are rotating. The strip 15 is thus cleaned at the commencement of the feed and therefore a considerable length of the strip is not allowed to pass between the rolls before the cleaning press is brought into action. Further the strip is fed between the rollers without any 20 liability of damage to the operator, whilst at the same time the feeding operation is considerably simplified.

Referring to the drawings:

Figure 1 is a side elevation of an appliance 25 constructed according to this invention.

Figure 2 is a plan of Figure 1, and

Figure 3 is a sectional elevation of a modified form of the invention.

According to one form of the invention, the 30 cleaner comprises a press the bottom jaw or bed 1 of which is mounted on a carrier frame or bracket 2 so that it is capable of movement towards or from the guide 3 mounted in front of the rolls. The upper pressure jaw or member 4 is slidably mounted on two vertical pillars 5 carried by the bed of the press, the pillars being connected across the top by a suitable stay member 6. The movable pressure jaw or plate is 35 pressed downwardly by means of spiral springs 7 mounted on the pillars 5, the pressure of which can be adjusted by means of abutment collars 8 having screwed engagement with the pillars 5. A quick action device is provided for raising or 40 lowering the upper pressure jaw or member 4 and this conveniently comprises a pair of toggle links 9 and 10 on each side of the press. The toggle links are pivoted respectively to the bed 2 of the press and the upper jaw or member 4 and also to a member 11 carried by an eccentric 45 strap 12. The eccentric strap for each pair of toggle links is mounted on an eccentric 13 carried by a transversely arranged shaft 14 to which a hand lever 15 is fixed. When the hand lever 15 is raised the eccentric 13 is rotated and effects 50 the movement of a spindle, on which the inner

ends of the toggle links are mounted, to one side, thereby enabling the upper pressure member to move down on the lower pressure member. When the said handle 15 is depressed the upper pressure member 4 is raised to open the jaws. The bracket 16 on which the cleaner press is movably mounted carries a guide roller 17 for the metal strip, and the upper pressure member is provided with curled or curved lugs 18 on each side to form hooks for receiving rods 19 which secure 10 canvas or other cleaning material to the pressure member.

The bracket 16 on which the bed 2 of the press is mounted has projecting side edges 20, and slide bars 21 fixed by studs to the sides of the bed of the press engage under such projecting edges, to slidably mount the press on the bracket. The bed 2 of the press is provided with a toothed rack 22 which is arranged longitudinally and centrally on the underside, and a toothed wheel 23, mounted on a spindle 24 carried by the said bracket is in engagement with the rack. A handle 25 is fixed on this spindle so that when it is raised or lowered the press is moved in a direction towards or from the rolls 26. Buffer springs 25 27 may be mounted on the bracket against which the front of the bed of the press bears when the rolling mill is in action.

According to a modified form of the invention as shown by Figure 3, the bed 2a of the press is 30 provided with a projecting portion 28 which forms a guide for the metal strip, the bed 2a of the press being slidably mounted on the frame 29 of the machine.

The guide in Figures 1 and 2 and in Figure 3 35 comprises a table having dove-tail slots 30, 31, in which bolts 32 are slidably mounted for adjustably fixing lateral guides 33 for the strip of metal. The wood block 34 under which the metal strip passes is fixed to the table by bolts, the 40 head of which engage in the slots 30.

With this construction therefore the strip of metal is first placed in the press with a portion projecting forwardly from the jaws. The lever 45 25 is then operated for moving the press forward to feed the said projecting end of the strip between the rolls. The rolls drawing the strip therethrough will exert a pull drawing the press against the buffer springs which will act as shock absorbers and prevent damage. The strip will 50 thus be cleaned at the commencement of the rolling operation and the operation of feeding the strip to the rolls is very considerably simplified and prevents any danger to the operator, particularly when the rolls are revolving at a 55

high speed. The form of the press may be considerably modified according to the pressure required. Any suitable form of spring pressure may be utilized or in lieu of springs hydraulic or any other form of pressure may be applied.

5 I claim:

10 A device for cleaning and feeding metal strips to the rolls of rolling mills, comprising a cleaning press, a carrier frame member, a bracket forming the bed of the press mounted to run in guides on said frame to be movable towards and away from the rolls, means for moving the bracket in the guides for feeding a metal strip gripped by the press to the rotating rolls, a mov-

able press jaw, means for fixing a fabric cleaning strip to such jaw, and means for guiding the strip to the rolls mounted to move with the bed of the press, comprising a portion of the bracket which extends forwardly of the press with the front edge adjacent the rolls when in action, lateral guides thereon for coacting with the edge of the metal strip and a wedge clamp for frictionally holding the metal strip against the face of the said portion of the bracket which extends forwardly of the press.
